Application September 17, 1932
Serial No. 633,598

8 Claims. (Cl. 12—145)

This invention relates to a method of making shoes, and contains in part subject matter common to application Serial No. 598,488, filed March 12, 1932.

5 The invention has for its principal object to afford a method of making soft or hard soled shoes of the welt type that are durable and may be produced at a lower cost of manufacture and of neater appearance than with processes heretofore 10 followed.

A further object of the invention is to afford a method by which an upper having a welt first 15 stitched thereto is lasted in a quick and economical way, the outer edge of the welt being then supported while the outer sole is cemented to it.

20 A further purpose of the invention is the provision of a method by which tacks can be done away with for holding the upper on to the last while the sole is cemented and a single instrumental 25 employed for lasting the upper and also supporting the welt while the outer sole is cemented to it.

Still another object of the invention is to afford 30 a method by which the lasting operation can be effected through clamping instrumentalities engageable between the welt and upper of a pre-welted shoe to draw the welt and edges of the upper under the last, such lasting means being left in position while the outer sole is cemented to the welt and serving as a support for the welt.

Another object of the invention is to further 35 reduce the cost of operation by applying cement to the under side of the welt before it is stitched to the upper and to ornament the upper side of the welt by the same operation that serves to cause the outer sole to adhere to the welt.

To these and other ends, the invention consists 40 in the method that will appear more clearly from the following description when read in conjunction with the accompanying drawing, the novel features being pointed out in the claims at the end of the specification.

In the drawing:

45 Fig. 1 is a transverse section of a last and a prewelted upper applied thereto, illustrating one possible way of carrying out the invention;

Fig. 2 is a similar view showing the filler and outer sole attached, with the clamping instrumentalities in position between the upper and 50 welt;

Fig. 3 is a side elevation of the parts illustrated in Fig. 1, and

Fig. 4 is an inverted plan view.

In carrying out the method according to the preferred procedure, the upper 1 is formed of

suitable material such as soft pliable leather, and a welt 2, which has previously been treated with latex or other suitable adhesive on its under surface, is stitched at 4 to the lower free edge of the upper.

The last is then inserted into the upper which is pulled over the bottom of the last by any suitable means such as a wire or other device until it is in proper position to receive the clamp that is positioned between the welt 2 and the adjacent edges of the upper 1, as shown in Fig. 2. By drawing the members of the clamp together and securing them in clamping position, the upper is tightly lasted entirely around the last and held in such position without the use of any other instrumentalities until the outer sole is attached.

If desired to use an insole, the latter is positioned between the under side of the last and the inturned edges of the upper and cemented to the upper, as shown in Fig. 1. While it is preferable to employ the clamp for effecting the lasting operation, as already described, the upper may be lasted in some other way and held in position by tacks 5, as in Fig. 1, until the clamp is applied, as in Fig. 2. But we prefer to use the clamp for both lasting and holding the upper, and thus entirely do away with the use of tacks, as at 5.

A suitable filler 6 is applied substantially flush with the lower surface of the welt before the outer sole 22 is secured in position, such filler being constructed of felt, or of granulated cork mixed with glue or cement and held in position by glue or cement.

The clamp employed for lasting the upper end for supporting the welt when the outer sole is cemented thereto comprises two parts 7 and 8 which are cut away on adjacent sides to afford an opening at the center adapted to conform to a last which it is designed to fit. The parts 7 and 8 are hinged together at one corner by a hinge member 9 which is preferably U-shaped in cross-section so as to embrace both sides of the parts 7 and 8. The hinge is pivoted to the parts 7 and 8 by means of pins or studs 11 and 12.

The parts 7 and 8 of the clamp are preferably in the form of plates of sheet metal and so constructed that when in clamping position, as shown in Fig. 4, the outer contour of the clamp is substantially that of a rectangle. The adjacent or meeting edges of the plates 7 and 8 are preferably along the straight lines 13 and 14, one of which extends from the corner to the central opening of the clamp while the other meeting line 14 is along the longitudinal axis of the clamp, the arrangement being such as to afford a maximum

60

70

75

80

85

leverage when drawing the clamping plates together.

One of the meeting lines between the plates of the clamp is embraced by the hinge 9 while the 5 other meeting line is embraced by a latch or locking member 15 which acts to draw the clamping plates into engagement with a shoe upper so as to last the same and hold it in such position while the outer sole is cemented to the welt. The latch 10 15 is pivoted at 16 to the part 7 and is substantially U-shaped in cross-section so as to embrace the opposite surfaces of the parts 7 and 8 to hold them in substantially the same plane. A stud or pin 17 in the latch is arranged to engage a notch 15 formed in the edge of the plate 8 and acts to retain the clamping members in tight engagement with the shoe. When the latch is swung on its pivot from engagement with the plate 8, the plates 7 and 8 are free to swing away from each other 20 and to release the shoe.

The clamping members or plates are substantially flat and arranged in the same plane except for a slight transverse bending at 18 and 19 so as to conform to the shape of the bottom of the last. 25 The shoe engaging portions or inner edges of the clamping plates defining the enlarged opening in the center are tapered downwardly and inwardly as at 21, to form a clearance for the upper on the upper side of the clamp, while maintaining a substantially plane surface on the under side of the 30 clamp for engaging and supporting the outwardly projecting free portion of the welt. That is to say, the upper tapered surface 21 and the lower substantially plane surface on the shoe engaging 35 edges of the clamp are shaped to conform to the space between the upper and welt and to enable the clamp to engage the upper tightly and draw it over the last to its proper position to receive the outer sole.

40 After the clamp is thus positioned, the outer sole 22 is cemented to the filler and welt, which latter has previously had an adhesive applied thereto, this operation being effected by placing the parts in a suitable pressure-applying machine 45 that holds the last with the upper, welt and clamp and permits forcing the outer sole against the welt under sufficient pressure to cause a tight and permanent adherence. During this operation, the under surface of the clamp supports 50 the free pliable edge of the welt so that the outer sole can be pressed against the welt with requisite pressure, and a uniformity of attachment secured between the welt and the sole. After the outer sole has been applied in this manner, the pressure 55 operation completed and the cement is set, the clamp is removed and the outer sole and welt finished in the usual manner.

By the use of such a clamp, a wide welt can be employed in a soft soled shoe, giving a greater 60 surface contact between the welt and outer sole and thus increasing the efficiency and durability of the product. Such a welt can be stitched to the lower edge of the upper, which would be formed so as to project to a greater extent under the last, or the welt could project inwardly over the last 65 beyond the upper if desirable.

The outer sole can be formed of either soft 70 pliable leather or of hard sole leather and after it is cemented to the welt in the manner described, the sole may be stitched to the welt as usual.

For the purpose of affixing the sole to the welt while the clamp is in lasting position between the edges of the upper and the welt, the clamp 75 and last may be supported and pressure applied

against the sole and welt, or the sole may be supported and pressure applied against the last and clamp, or pressure may be applied against the last, clamp, and sole, as may be desired to bring about a uniform distribution of pressure over the entire meeting surfaces between the welt and sole.

It is usually desirable to form a fluted or other design on the upper or outer surface of the welt, and with the present method, such a design can be formed in the welt during the pressure-applying operation. To effect this, the lower surfaces of the clamping members at the shoe engaging portions are formed with a sharp fluting design 23 adjacent to and surrounding the enlarged opening at the center of the clamp. When the clamping plates engage the upper in lasting relation, the fluting design rests upon and engages the upper surface of the welt, so that when pressure is applied to the outer sole, the welt is pressed into close contact with the clamp and the imprint of the fluting design is thereby transferred to the welt.

The method may be practiced in various ways without departing from the underlying novel features of the invention, and this application is intended to cover any departures or modified procedures coming within the spirit of the invention or the scope of the following claims.

We claim:

1. The method of making shoes which consists in forming an upper, attaching a welt to the upper, clamping the upper on to a last by instrumentalities located between the upper and welt, cementing a sole to the welt by applying pressure to the sole and welt against said clamping instrumentalities, and simultaneously forming a design on the upper surface of the welt through the pressure against said clamping means.

2. The method of making shoes which consists in forming an upper, stitching a welt to the upper, and lasting the upper by first positioning between the welt and upper a substantially L-shaped clamping plate having a tapered edge which engages closely between the welt and upper entirely across the toe portion, along one side, and across a part of the heel portion, and thereafter bringing into clamping relation a complementary plate having a tapered edge which engages closely between the upper and welt along the other side and the remaining part of the heel portion.

3. The method of making shoes which consists in forming an upper, stitching a welt to the upper, and lasting the upper by positioning between the upper and welt a substantially L-shaped clamping plate having a tapered edge that engages closely between the welt and upper and extends entirely across the toe portion, along one side, and across a part of the heel portion and thereafter bringing a complementary clamping plate having a tapered edge which engages closely between the upper and welt into engagement with the other side and remaining part of the heel portion about a pivot at one end of the first mentioned plate.

4. The method of making shoes which consists in forming an upper, stitching a welt to the upper, and lasting the upper by moving a substantially L-shaped plate having a tapered edge laterally into close contact between the upper and welt into engagement with the entire toe portion, one side, and part of the heel portion of the upper and thereafter bringing a

- complementary plate having a tapered edge which engages closely between the upper and welt by a swinging motion around one end of the first mentioned plate into engagement with the other side and remaining part of the heel portion. 5
5. The method of making shoes which consists in clamping an upper on to a last by first moving a substantially L-shaped plate having a tapered edge laterally into close contact between the upper and welt into engagement with the entire toe portion, one side, and part of the heel portion, thereafter positioning a complementary plate having a tapered edge into close contact between the upper and welt in engagement with the other side and remaining part of the heel portion, and holding said plates in clamping relation while cementing a sole to the welt by pressure of the latter against said plates. 10
6. The method of making shoes which consists in forming an upper, stitching a welt to the upper, clamping the upper to a last by first moving a substantially L-shaped plate having a tapered edge laterally into close contact between the upper and welt into engagement with the entire toe portion, one side, and a part of the heel portion, thereafter positioning a complementary plate having a tapered edge into close contact between the welt and upper in engagement with the other side and remaining part 15
- 30 of the heel portion by a swinging movement of the second plate with relation to the first plate, and cementing a sole to the welt while pressing the latter against said plates. 80
7. The method of making shoes which consists in forming an upper, applying cement to the inner surface of a welt, thereafter stitching the welt to the upper, lasting the upper, holding the upper on the last by clamping plates shaped to conform to the last and applied between the upper and welt, and applying cement to a sole and affixing the sole to said welt by pressure while the upper is held in place on the last by said clamping plates. 85
8. The method of making shoes which consists in forming an upper, applying cement to the inner surface of a welt, thereafter stitching the welt to the upper, lasting the upper by moving a plate laterally between the upper and welt and thereafter swinging a complementary plate about a pivot on the first plate and thereby moving the complementary plate between the welt and upper by a lateral swinging movement, said plates having tapered edges that engage closely between the upper and welt entirely around the shoe, locking the plates in clamping relationship, and cementing a sole to the welt while pressing the latter against said plates. 90
